UNITED STATES PATENT OFFICE.

WILLIAM R. GRUBER, OF NEW YORK, N. Y.

CONTAINER-RIM PROTECTOR.

Application filed August 3, 1928. Serial No. 297,177.

This invention relates to container rim protectors as used in connection with food containers, and one object of this invention is to provide means whereby the outer edges of food containers are protected from injury. A further object is to improve the appearance of the containers and also provide sanitary protection for the same.

These and other objects are attained by the 10 novel combination, construction and arrangement of various parts, as described in this specification, and illustrated in the accompanying drawing, in which:

Figure 1 is a perspective view of a food 15 container provided with a removable type of sanitary protecting ring made in accordance with the invention, partly broken to disclose its novel features.

Figure 2 is a side elevational view of the 20 same partially in section.

Figure 3 is a similar view showing a modified form of construction.

Food containers, cooking pots, vessels and other similar equipments, as used in restaurants, cafeterias, hotels, etc. are subject to 25 very severe usage, and occasionally parts of such containers break off, the protecting enamel chip, or other severe damage is done by such usage.

The portion 15 most subject to such treatment is the uppermost lip or rim, as may be observed where such food containers are in service.

A broken or chipped lip or rim of such containers is not only very unsightly, but also 35 exceedingly insanitary, as the broken, rough surface and crevices are favorite sheltering places for all kinds of deposits, dirt, and disease germs.

It is also a fact that such broken rims are 40 never kept clean, and when washed, little or no attention is paid to these broken or chipped portions, consequently they present a permanent source of danger to the health of the public.

To overcome such decidedly insanitary conditions, and at the same time add to the attractiveness of the containers, there is provided a specially designed protecting covering for the rim or lip of such containers.

In the drawing the numeral 10 designates 50 generically a conical cooking vessel of ordinary type suited to contain foods which are to be kept warm, these vessels having on their larger upper portions an outstanding annular

flange 11, above which is an outturned beaded edge 12.

A hot plate 13 is commonly used to support such vessels, the plate having circular openings to receive their lower tapered portion, 60 the flange 11 resting on the plate at the margin of the openings.

In the simpler form of the device, as shown in Figures 1 and 2, a covering, composed of any suitable material is passed over the beaded edge of the container, this covering being composed of an outer skirt portion, curved inwardly to closely overlie the bead, as at 16, and present an inner ring member 17 disposed within the edge of the vessel. 65

In the type shown in Figure 3, the skirt portion 18 may be spun to closely fit the neck 14 of the container, present a bead 19 over the flange 11 and another bead 20 to enclose the rim 12, the inner element 21, extending 70 slightly within the vessel.

Although the foregoing describes the invention, it is not desired to be limited to the exact construction shown, it being apparent that there may be considerable variations in 80 utilizing the principles disclosed, without departing from the spirit of the invention as claimed.

Having thus described the invention, what is claimed as new and desired to be secured by 85 Letters Patent, is:—

1. The combination with a container having a beaded rim and a flange spaced therebelow, of a metal guard ring tightly engaged over said beaded rim and extending downwardly to enclose said flange. 90

2. The combination with a conical container having an outstanding beaded rim and an annular outstanding flange spaced in parallel therebelow, said rim and flange being 95 substantially equal in diameter, of a metal guard permanently secured to said rim to envelop the same and a skirt portion of said guard extending over and being secured to said flange.

3. The combination with a conical container having an outstanding beaded rim and an annular outstanding flange spaced in parallel therebelow, the rim and flange being uniform in diameter, of a metal guard permanently secured to said rim to tightly enclose the same, said guard having a cylindrical extension to engage the container flange. 105

In testimony whereof I affix my signature.
WILLIAM R. GRUBER.
